UNITED STATES PATENT OFFICE.

HARVEY L. COCHRAN, OF SHERIDANVILLE, PENNSYLVANIA.

FIRE-DOOR-CLOSING DEVICE.

SPECIFICATION forming part of Letters Patent No. 752,825, dated February 23, 1904.

Application filed April 9, 1902. Serial No. 102,086. (No model.)

To all whom it may concern:

Be it known that I, HARVEY L. COCHRAN, a citizen of the United States, residing at Sheridanville, in the county of Allegheny and State of Pennsylvania, have invented a new and useful Improvement in Fire-Door-Closing Devices, of which improvement the following is a specification, reference being had therein to the accompanying drawings, in which—

10 Figure 1 indicates an elevation of my improved device for closing fire-doors, the doors being open. Fig. 2 is a plan view showing the position of the doors while being closed. Fig. 3 is an enlarged detail of the weight-supporting mechanism, and Fig. 4 is a perspective view of the door-tripper.

My invention relates to improvements in fire-doors, and particularly to means to automatically close the doors in the event of fire.

20 It also relates to means to cause the overlapping door to close immediately after the door which it overlaps.

Heretofore, so far as I am aware, it has been unsafe to push such door back against or parallel with the wall, for the reason that when in such position it is impossible in the event of fire to close the same quickly (or even close the same at all) by the devices now employed. It also frequently happened that the overlapping door closed first, forming when the other door closed thereon a space through which flame could readily pass.

The objects of my invention are to produce a device applicable for automatically closing fire-doors which will permit the doors to be pushed back against the walls out of the way when opened and yet permit the same to close quickly in the event of fire and also to prevent the overlapping door from closing first.

40 To accomplish these objects, my invention consists in the novel construction and arrangement of parts hereinafter more specifically described, reference being had to the accompanying drawings, which form a part of this specification, in which like reference characters indicate like parts wherever they occur throughout the several views.

Referring to said drawings, 1 and 2 are doors supported on hinges 3 and adapted to 45 close the opening, as hereinafter described.

One of said doors, 2, is provided with a plate 5, secured upon its outer edge in any suitable manner and adapted to overlap the edge of the door 1 when said doors are closed for the purpose of more completely closing the opening 4. 55 To the inner edge of each of said doors 1 and 2, at the top thereof, is attached a flexible connection 6 or 6', formed of rope, chain, or wire, which respectively pass over sheaves 77', the said sheaves being mounted on the plate 9, secured upon the top of the frame of the door, the sheaves being substantially in vertical alignment with the inner edge of each of said doors. The said ropes or chains pass, respectively, to the opposite edge of the respective doors to 65 which they are attached over the double sheaves 10 and 11, which are respectively mounted in any suitable manner upon the plate 9, and through a block secured upon the top of the heavy counterweight 13, which is 70 detachably suspended from one arm of the bell-crank 14. The free ends of said connections, respectively, have attached thereto the light counterweights 12 for the purpose of taking care of the slack of said connections. 75 The said bell-cranks are pivotally secured upon the door-frame and their vertically-projecting members connected to cords or chains 15, the opposite ends of which are connected to vertically-disposed links 16 16, the lower ends of 80 which are pivotally secured upon the plate 9. 17 is a cord in which a fusible plug or fusible connection is inserted, which is connected to both of said links, and so long as the fusible portion thereof remains intact serves to hold 85 the links in vertical position, as shown in Fig. 1, and also to support the heavy counterweights suspended on the horizontal members of the bell-cranks.

18 is a tripper arranged upon the top frame 90 of the door in such wise as to engage the tops of the doors, respectively. One member, *a*, of said tripper is provided with a vertically-disposed face and is adapted to arrest the door 2 in closing until the door 1 in engaging the 95 under curved surface of the member *b* has swung the tripper upwardly on its hinges *c*, thus permitting door 1 to close in advance of door 2, as shown in Fig. 2.

19 19 are outwardly-projecting brackets 100

arranged, preferably, in vertical alinement with the hinges of the doors, respectively, upon the outer ends of which are respectively mounted sheaves 20 20, over which the ropes 5 6 6' pass when the doors are opened to their fullest extent, as shown in Fig. 2, dotted lines, so that in the event of the fusible connection being in any wise severed the heavy weight 13 can readily and quickly close the doors.

10 Having described my invention, what I claim, and desire to secure by Letters Patent, is—

1. In an automatic door-closer, the combination with a door, of a flexible connection attached to the door, permanently-positioned supports over which the flexible connection runs, means for keeping the flexible connection taut over said supports, normally inactive means adapted to engage the flexible connection between the supports to pull said connection therebetween and cause closing of the door, and means adapted to cause the action of the normally inactive means aforesaid.
2. In an automatic door-closer, the combination with a door, of a flexible connection attached to said door, permanently-positioned supports over which said flexible connection runs, means for holding the flexible connection taut on said supports, a weight adapted 25 to engage the flexible connection between the supports aforesaid, and means for holding said weight normally inactive and for automatically causing the release thereof.
3. In an automatic door-closer, the combination with a door, of a flexible connection attached thereto, permanently-positioned supports over which said flexible connection runs, means for keeping the flexible connection taut on said supports, a weight adapted to engage 30 the flexible connection between the supports aforesaid, means for sustaining said weight and normally preventing it from falling, and a fusible connection controlling said weight-supporting means.
4. In an automatic door-closer, the combination with a door, of a flexible connection attached to the door, permanently-positioned supports over which the flexible connection runs, means for keeping the flexible connection taut over said supports, normally inactive means adapted to engage the flexible connection between the supports to pull said connection therebetween and cause closing of the door, and means adapted to cause the action of the normally inactive means aforesaid.

nation with a door, of a flexible connection attached to the door, means for automatically operating said flexible connection to close the door, and a point of bearing from which the flexible connection is disengaged when the door is closed but over which the flexible connection is made to run when the door is opened which point of bearing is located beyond the face of the door in position to cause the flexible connection to exert a leverage on the door 50 to tend to close the door.

5. In an automatic door-closer, the combination with a pair of doors, of means for automatically closing said doors, means engaging one of the doors when nearly closed and momentarily retaining it until the other door has closed, and means for thereafter releasing the retained door to permit closing thereof.

6. In an automatic door-closer, the combination with a pair of doors and means for automatically closing said doors, of a member engaging one of the doors when nearly closed and momentarily retaining said door, and a member engaged by the door first closing which releases the engagement of the first- 65 mentioned member with the other door and permits said door to close, whereby the doors are closed one after the other.

7. In an automatic door-closer, the combination with a pair of doors and means for causing said doors to automatically close, of a two-armed hinged bracket, one of the members of which engages one of the doors and momentarily retains it until the other door has closed, the other member of said bracket 70 being engaged by the door first closing to release the engagement of the bracket with the retained door.

In testimony whereof I have hereunto signed my name in the presence of two subscribing 85 witnesses:

HARVEY L. COCHRAN.
In presence of—

CLARENCE A. WILLIAMS,
JOHN H. RONEY.
